UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed May 4, 1920. Serial No. 378,789.

To all whom it may concern:

Be it known that I, ORA A. COLBY, a citizen of the United States, and a resident of Irwin, in the county of Westmoreland 5 and State of Pennsylvania, have invented a new and useful Improvement in Electric Furnaces, of which the following is a specification.

My invention relates to electric furnaces and particularly to melting furnaces of the electric-resistance type, and it has for one of its objects to provide a furnace in which the resistor is located in close thermal contact with a container for the metal being melted.

Another object of my invention is to provide a solid-block resistor of refractory electrical-conducting material and improved means for conducting the current to and from the resistor, which means will, in addition, prevent rapid deterioration of the resistor blocks.

In practicing my invention, I provide a suitable container for the metal being melted, mounting the same in a refractory casing; a block resistor located beneath and supporting said container, hoppers adjacent the ends of said resistor blocks, solid terminal electrodes projecting into said hoppers, and masses of granular electrical-conducting material in said hoppers electrically connecting the electrodes and the resistor blocks.

In the single sheet of drawings, Figure 1 is a top plan view of a furnace embodying my invention; Fig. 2 is a view, partly in rear elevation and partly in section, on the line II—II of Fig. 1, and Fig. 3 is a cross-sectional view of the same furnace on the line III—III of Fig. 1.

The supporting structure of the furnace comprises an exterior metal casing or frame 1 which encloses an outer shell 2 built up of heat-insulating brick, and an inner shell 3 built up of fire brick. A number of bricks or slabs 4 of a suitable highly refractory material partly surround and support a resistor 5 which comprises one or more bricks or blocks of carborundum or silicon carbide.

A container 6 for the metal to be heated may consist of any suitable material used for such purposes but I prefer to use alundum sintered in place, as this material has a high heat conductivity and is not attacked by molten non-ferrous metals. The

resistor 5 is located immediately beneath, and in close thermal contact with, the bottom of the container 6 so that the heat generated by the resistor will readily flow through the bottom of the container and into the contents thereof. The container 6 is provided with a suitable extension 7 in which is formed a pouring trough 8 for the molten metal. Opposite, and adjacent to, each end of the resistor blocks 5, a hopper or well 9 is formed in the brick work, the resistor blocks 5 extending a short distance into these hoppers or wells. At the bottom of each hopper is placed a terminal electrode which comprises a solid block of graphite or amorphous carbon. A terminal plate 11 is suitably secured to the outer end of each of the electrodes 10 and projects through the casing 1 for connection to an electric supply circuit conductor (not shown). The terminal electrode 10 is made relatively long so that the outer end to which the terminal plate 11 is connected shall be a relatively large distance away from the resistor proper and will therefore not be subjected to the high temperature of the resistor itself.

A mass 12 of electrical-conducting granular material, such as graphite or coke, is placed in each of the hoppers 9 and, as its cross-section is made relatively large, it provides a current path of relatively low resistance between the electrode 10 and the resistor blocks 5. Where a solid refractory resistor is used to obtain a relatively high temperature, as is required to melt certain non-ferrous alloys, a relatively rapid deterioration of the resistor blocks occurs at the place where contact is made with a metallic conductor terminal, especially if this contact is exposed to the atmosphere and if it is subjected to a relatively high temperature. This deterioration is prevented by using finely divided electrical-conducting material to provide numerous current paths to the resistor blocks. Some of the granular material oxidizes during the operation of the furnace so that the contact resistance increases but the open hoppers permit of repacking the granular material when any appreciable amount thereof has been oxidized and of removing and completely renewing the material whenever necessary. The granular material also protects the terminal electrodes 10 from being overheated,

as it provides a low-resistance-current path therefrom.

A suitable cover member (not shown) may be used, if desired, to prevent radiation of heat from the upper surface of the furnace casing and from the container itself during the operation of the furnace.

A plurality of suitable brick piers 13 are provided which carry suitable bearing members 14 for co-operation with short shaft extensions 15 secured to the metal casing 1 to permit of tilting the entire furnace to pour the molten metal.

I thus provide an electrical furnace in which a block resistor is used to generate the heat and to support the container and in which the method of conducting the current to and from the resistor permits of substantially uninterrupted operation of the furnace with a relatively small deterioration of the resistor blocks.

While I have shown a specific embodiment of my invention, various changes may be made therein without departing from the spirit and scope of my invention, and I desire that only such limitations shall be placed thereon as are imposed by the prior art or are specifically set forth in the appended claims.

30 I claim as my invention:

1. In an electric furnace, the combination with a container, of a resistor comprising solid blocks of refractory electrical-conducting material beneath, and adapted to support, said container, terminal electrodes, and a mass of electrical-conducting granular

material interposed between each of the electrodes and the resistor to prevent overheating of the electrodes.

2. In an electric melting furnace, the combination with a container of refractory material, of a resistor located beneath, and supporting, said container, said resistor comprising solid blocks of refractory electrical-conducting material in contact with one another, hoppers located opposite the ends of the resistor, solid carbonaceous terminal electrodes in said hoppers and a mass of electrical-conducting granular material in said hoppers adapted to conduct current from said electrodes to said resistor and to prevent overheating and consumption of said electrodes.

3. In an electric melting furnace, the combination with a container, a refractory casing for said container, and means for tilting said container and said casing, of a resistor located beneath said container and comprising solid blocks of refractory electrical-conducting material to constitute a support for said container, hoppers located opposite the ends of said resistor, solid carbonaceous terminal electrodes at the bottom of said hoppers, and a mass of electrical-conducting granular material in said hoppers adapted to conduct current from said electrodes to said resistor to prevent overheating and consumption of said electrodes.

In testimony whereof, I have hereunto subscribed my name this 19th day of April, 1920.

ORA A. COLBY.
